UNITED STATES PATENT OFFICE.

DONALD G. McDougall, OF IPSWICH, QUEENSLAND, AUSTRALIA.

SPARK-ARRESTER.

1,333,323.

Specification of Letters Patent. Patented Mar. 9, 1920.

Application filed July 12, 1919. Serial No. 310,450.

To all whom it may concern:

Be it known that I, DONALD G. McDougall, a subject of the King of England, residing at Ipswich, in the State of Queensland, and 5 country of Australia, have invented certain new and useful Improvements in Spark Arresters, of which the following is a specification.

The invention relates to means for preventing the escape of sparks and incandescent particles which has proven dangerous in causing out-buildings and fields to take fire.

The invention provides spark arresting 15 means particularly adapted for locomotives which will not materially interfere with the forced draft which is essential to maintain a hot fire for the quick generation of steam.

The drawings illustrate a preferred embodiment of the invention. However, it is to be understood that in adapting the same to meet different conditions, various changes in the form, proportion, and minor details of construction may be resorted to without 25 departing from the nature of the invention as claimed hereinafter.

In the drawings hereto attached,

Figure 1 is a longitudinal section of the forward portion of a locomotive boiler provided with spark arresting means embodying the invention.

Fig. 2 is a transverse section on the line 2—2 of Fig. 1 looking to the rear.

Fig. 3 is a horizontal section on the line 35 3—3 of Fig. 1.

Figs. 4 and 5 are detail views of the portion of the perforated baffle plates.

Corresponding and like parts are referred to in the following description and indicated 40 in the several views of the drawings by like reference characters.

The drawings illustrate the application of the invention to a locomotive boiler of ordinary construction, the numeral 1 designating 45 the body of the boiler, the numeral 2 an end flue plate and 3 the smoke box at the forward end of the boiler, the same being mounted upon the saddle 4 of the engine and having the smoke stack 5 connected thereto.

50 A chute is connected with the lower forward portion of the smoke box and comprises a funnel-shaped portion 6 and a tubular portion 7, said chute being closed at its lower end by means of a swinging cover 8 which is held in closed position by a weighted arm 9. A suitable connection 10 is attached to

the weighted arm 9 and extends into the cab of the locomotive or to other convenient position to be operated when it is required to swing the cover 8 into open position to admit of ashes and like accumulations escaping from the chute. A pipe 11 connects with the lower portion of the chute near the outlet thereof and supplies a medium for positively clearing the ashes or other accumulations from the chute when the cover 8 is open. The pipe 11 preferably connects with the water space of the boiler and is provided with a controlling valve 12 which is adapted to be opened or closed by the engineer. 70 When the cover 8 is open and water from the boiler permitted to discharge into the chute the accumulation in the latter is quickly and thoroughly discharged.

The numeral 13 designates the branch 75 pipes by means of which the steam is conveyed from the boiler to the side cylinders, not shown, of the engine in a manner well understood. Said branch pipes connect with the main pipe 14 which is in communication with the steam space or dome of the boiler in a manner well understood. The numeral 15 indicates the ordinary blast pipe which receives the exhaust from the cylinders of the engine. The blast pipe 15 is in 80 line with the smoke stack 5 and terminates in a nozzle 16. A funnel-shaped screen 17 connects the delivery end of the blast pipe with the lower or receiving end of the smoke stack and serves to prevent the escape of any 85 sparks which may reach the screen.

A plurality of baffle plates is disposed within the smoke box. These plates are arranged substantially, as indicated in Fig. 1 and are supported by the side walls of the 95 smoke box preferably by means of angle irons 18. Obviously the plates may be supported in any desired way. The plates may be of unitary or sectional formation as found most advantageous to admit of access to the parts for repairs or any other purpose. Beginning at the front end of the smoke box the baffle plates are designated successively by the letters A, B, C, D and E. The baffle plate A is located near the top 100 of the smoke box and inclines rearwardly and downwardly and is imperforate. The baffle plate B is inclined slightly to the vertical and has its upper edge in contact with or joining the lower rear edge of the baffle 105 plate A. The baffle plate E is perforated and inclines downwardly and rearwardly

from its upper forward edge. The baffle plate C is perforated and inclines downwardly and rearwardly from the lower edge of the baffle plate D and terminates a short distance from the bottom of the smoke box and about in line with the blast pipe 15. The baffle plates B and C are of sectional formation and the middle sections are hinged to admit of their being turned aside when it is required to gain access to the interior of the smoke box for any purpose through the front thereof which is closed by a cover 19 in a manner well understood. The baffle plate D is imperforate and is relatively narrow and is disposed a short distance from the bottom of the smoke box and has the front edge in close contact with the lower edge of the baffle plate C. The baffle plate B inclines slightly to the horizontal in an upward and rearward direction from its junction with the baffle plate C. The baffle plate E is likewise imperforate and inclines upwardly and rearwardly from its lower edge which makes a close joint with the rear edge of the baffle plate B. The baffle plate E is of sectional formation and the middle section is hinged at its upper edge, as indicated at e to admit of such section being moved aside when access to the flue plate 2 is required. A plate 20 secured to the flue plate 2 extends horizontally therefrom and makes close connection with the upper edge of the baffle plate E. The baffle plates C and E incline upwardly in opposite direction with the baffle plate D between their lower edges.

In practice the smoke and products of combustion escaping from the flues of the boiler enter the smoke box at a point below the plate 20 and strike the forwardly and downwardly inclined imperforate baffle plate E and as a result the major portion of the sparks and incandescent particles is thrown downward into the lower portion of the smoke box and is swept forwardly by the current into the funnel portion 6 of the ash chute. As the products of combustion reach the lower portion of the baffle plate E they are directed forwardly and downwardly by the baffle plate D and are caused to sweep across the lower portion of the smoke box and thence upwardly at the front end thereof when they meet the imperforate baffle plate A and are again deflected rearwardly and downwardly. Any sparks or incandescent particles striking the baffle plate A are deflected downwardly into the lower portion of the smoke box whereas the products of combustion pass through the openings of the perforated baffle plates B and C, thence through the meshes of the screen 17 and escape through the stack 5. The screen 17 is of such formation as to remove the last traces of sparks to prevent the escape of the same into the open air.

65 The baffle plates B and C are constructed

substantially, as indicated in the detail views, Figs. 4 and 5, the body of the plate being designated by the letter B and the openings therein by the letter b. The openings b are countersunk to facilitate the passage of the products of combustion and the escape of any ashes that may tend to accumulate above the perforated plate. The openings b extend through the plate at a right angle thereto, hence the walls of the openings assist materially in deflecting sparks and incandescent particles so as to prevent their passage through the openings.

When access to the interior of the smoke box is required for any purpose the plate 19 is removed and the middle sections of the baffle plates B and C swung to one side and the middle section of the baffle plate E either turned aside or removed, the latter result being attained by having hooks at the upper edge of the middle section engaging openings in an angle iron 21 at the forward edge of the plate 20. Suitable fastening means are provided for securing the movable sections of the baffle plates, the same being indicated at 22.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In a steam boiler provided with a smoke box, a depending baffle plate at the inner or rear end of the smoke box and an upwardly and forwardly inclined perforate baffle plate in the forward portion of the smoke box and having close connection at its lower edge with the lower portion of the depending baffle plate and having close connection at its upper forward edge with the front of the smoke box.
2. In a steam boiler provided with a smoke box, a depending imperforate baffle plate in the rear portion of the smoke box, an imperforate baffle plate in the upper forward portion of the smoke box and a downwardly and rearwardly inclined perforate baffle plate between the two imperforate baffle plates.
3. In a steam boiler provided with a smoke box, a plurality of baffle plates disposed within the smoke box and extending transversely thereof and arranged at various angles, the intermediate baffle plates including movable sections to facilitate access to the interior of the smoke box for any desired purpose.
4. In a steam boiler provided with a smoke

box, a downwardly and forwardly inclined imperforate baffle plate in the rear portion of the smoke box, a forwardly and downwardly inclined baffle plate in the lower portion of the smoke box having close connection with the lower portion of the first mentioned baffle plate, an upwardly and forwardly inclined perforate baffle plate making close connection with the lower portion of the second mentioned baffle plate and other baffle plates interposed between the upper portion of the perforate baffle plates and the front of the smoke box.

5. In a steam boiler provided with a smoke box, said smoke box having a smoke stack and a blast pipe in line with each other and a screen between the delivery end of the blast pipe and the receiving end of the smoke

stack, a baffle plate in the lower portion of the smoke box in line with the blast pipe and inclining slightly to the horizontal in an upward and rearward direction, an imperforate baffle plate inclining upwardly and rearwardly from the rear portion of the aforesaid baffle plate, a perforate baffle plate inclining upwardly and forwardly from the forward edge of the first mentioned baffle plate and other baffle plates between the upper forward edge of the perforate baffle plate and the front of the smoke box.
